(57) **CLAIM**

I claim the ornamental design for a mounting block for a printing element, as shown and described.

DESCRIPTION

FIG. 1 is a perspective view of a mounting block for a printing element as shown in my new design;

FIG. 2 is a second perspective view thereof;

FIG. 3 is a top plan view thereof;

FIG. 4 is a bottom plan view thereof;

FIG. 5 is a front elevation view thereof; the back side being a mirror image; and,

FIG. 6 is a right elevation view thereof; the left side being a mirror image.
